G. W. OWEN,
DETACHABLE HEEL,
APPLICATION FILED MAR. 11, 1920.

Patented Dec. 13, 1921.

UNITED STATES PATENT OFFICE.

GEORGE W. OWEN, OF INDIANAPOLIS, INDIANA, ASSIGNOR OF ONE-HALF TO PAUL K. THIRY, OF INDIANAPOLIS, INDIANA.

DETACHABLE HEEL.

1,400,095.

Specification of Letters Patent. Patented Dec. 13, 1921.

Application filed March 11, 1920. Serial No. 364,991.

To all whom it may concern:

Be it known that I, GEORGE W. OWEN, a citizen of the United States, residing at Indianapolis, in the county of Marion and 5 State of Indiana, have invented certain new and useful Improvements in Detachable Heels; and I do declare the following to be a full, clear, and exact description of the invention, such as will enable others skilled 10 in the art to which it appertains to make and use the same.

This invention relates to improvements in detachable heels for ladies' shoes.

Inasmuch as heels of the above mentioned 15 type are subject to much wear and breakage, and as the lifts, with which they are provided, become worn easily and have to be frequently replaced, I have devised a heel of novel construction which will permit easy 20 and ready removal of the old heel or the lift for the purpose of replacing either of them. The construction of my heel is such that it will enable unskilled persons to attach and remove their own heels or lifts, 25 thereby saving time and greatly reducing an expense which is otherwise necessary. I am aware that my idea is not broadly new, however, I am satisfied, and believe that the construction and arrangement I employ is new 30 and novel and will greatly increase the effectiveness of heels of this type; will be stronger, will insure quick and easy attachment and removal, and yet will be as inexpensive as any other similar ones.

35 Other objects and advantages of the invention will be apparent during the course of the following description.

In the accompanying drawings forming a part of the specification and in which like 40 numerals are employed to designate like parts throughout the same:

Figure 1 is a sectional view of a heel constructed in accordance with my invention, the same being shown applied to a shoe.

45 Fig. 2 is a perspective view of the shoe and heel detached.

Fig. 3 is a perspective view of some of the parts of the heel disassembled.

Fig. 4 is a sectional view of the heel provided with a special rubber lift which I contemplate using if desirable.

Referring to the drawings, wherein for the purpose of illustration is shown a preferred embodiment of my invention, the number 1 indicates the shoe, while 2 design-

nates, as a whole, my improved heel. The latter is preferably made from a hollow aluminum casting which is closed at its top by a plate-like portion 3 and is provided at its opposite end with a cavity or recess 4, 60 the bottom of which is in a form of an apertured partition 5. Portion 3 is provided with a non-circular socket 6 for the reception of a depending projection 7 which is carried by a plate 8 designed for permanent attachment to the outer surface of the shoe sole. This construction will prevent twisting or rotation of the heel and will hold it securely in place. This projection is provided with a threaded hole which is adapted 70 to align with the holes in the heel, when the projection is seated in the socket. A nail anchoring block 9 of wood or the like is placed in the cavity 4 and has its bottom face spaced by the bottom edge of the heel. 75 This block serves as a means for partially retaining the leather lift 10 in place as will be seen from the following description. Two layers of material are used to make up the lift and the top one 11 is smaller than the 80 other one which is of a size to neatly fit against the bottom of the heel in the usual way. The part 11 of the lift is to be projected into the recess 4 so as to abut the block 9 in the manner shown in Fig. 1. When in 85 this position the lift will be secured against displacement by nails 12 which pass through it and into the block 9. Emphasis is to be laid on this particular construction. First, because the lift by being provided with the 90 part 11 will not easily come off, which it might otherwise do. Second, by making this lift as shown, the nails 12 may be driven straight into the block 9 instead of having their inner ends clenched as they usually are. 95 In this way the lift may be removed and the tread layer thrown away while the other layer and block may be retained and used again. Hence, it will be necessary only to purchase a tread lift when repairing the 100 shoes. This method of repairing will be very inexpensive. In order to insure the lift against any possible displacement and at the same time to provide means for securing the heel in position, I employ a screw 13 105 which extends through the lift 10, heel 2, and has threaded connection at its inner end with the threaded hole in the projection 7. The head of the screw is thus embedded in the lift 10 and the screw may be conven- 110

iently removed whenever desired or necessary.

In Fig. 4 I have shown a rubber lift 14 instead of a two-part leather lift. A metal member 15 is embedded in this lift so as to prevent the head of the screw 13 from pulling through it and destroying it as it might otherwise do. In this showing of the invention, the screw 13 serves as the sole means 10 for retaining the lift in position, and it, of course, serves to secure the heel to the sole of the shoe.

In all probability the lift will become worn before the heel is damaged. It may be 15 readily removed by removing the screw 13 and prying the tread layer of the lift off. As before stated, the tread layer only need be replaced, because the parts 9 and 11 will be found in good condition. The manner in 20 which the parts are replaced is obvious and need not be explained. The heel may be likewise removed when it has been damaged sufficiently.

My heel is simple and effective, is easy to 25 make use of, is strong and durable, and is inexpensive.

A careful consideration of the foregoing description taken in conjunction with the drawings will enable the reader to acquire 30 a clear understanding of my heel. Further description is therefore deemed unnecessary.

It is to be understood that the form of my 35 invention shown in the drawings and described is to be taken as a preferred embodiment of the same, and that various minor changes in the shape, size, and arrangement

of parts may be resorted to without departing from the spirit of the invention or the scope of the adjoined claims.

I claim:

1. A shoe heel comprising a hollow body closed at its top and provided therein with a diamond-shaped socket, a plate for attachment to the sole of the shoe, said plate being provided with a depending projection of a 45 shape corresponding to the socket into which it is inserted, said projection having a screw-threaded hole therein, an apertured lift anchoring block, a lift attached thereto, and a screw passing upwardly through the lift anchoring block and body member, its inner end having screw-threaded connection with the opening in the projection, the head of the screw being embedded in the block. 50

2. In a heel structure, a metallic plate at- 55 tachable to a sole, a hollow body member closed at its top, one of said members having an angular recess and the other having an angular projection to engage in said recess to prevent relative rotation of the two, and 60 means to fasten the body to the plate.

3. A detachable heel member comprising a hollow body closed at its top, a partition substantially midway between its upper and lower ends to form a downwardly-opening 65 chamber, there being holes through the partition and the top of the heel adapted for a screw to fasten the member to a shoe.

In testimony whereof I have hereunto set my hand.

GEORGE W. OWEN.
